UNITED STATES PATENT OFFICE

HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

RESCUE TANK

Application filed August 28, 1930. Serial No. 478,323.

This invention relates to devices for use with disabled submarine boats, and more particularly to what I term a rescue tank.

It is known to provide submarine boats with access hatches through which the personnel can escape if the boat is disabled and lies submerged in comparatively shallow water. The escape of the personnel in this manner is not possible, however, when the boat is submerged in deep water where high pressures obtain. One of the main objects of my invention is to provide a rescue device or tank having associated therewith means operable from within the tank for drawing such tank into position upon the hatch cover of a disabled submarine boat. A further object is to provide means associated with the boat and adapted for cooperation with the tank, such means being so disposed as not to occupy valuable space within the hull of the boat. Further objects and advantages of my invention will appear from the detailed description.

In the drawings:

Figure 1 is a sectional view through an access hatch trunk and associated parts of a submarine boat, illustrating a part of my invention as applied thereto;

Figure 2 is a sectional view through the access hatch trunk and associated parts of a submarine boat and a rescue tank seated upon the main hatch cover, in accordance with my invention;

Figure 3 is a detail, partly in section, of the drum operating means; and

Figures 4 to 10, inclusive, are semidiagrammatic views illustrating the successive steps in the use of my invention in effecting rescue of the personnel of a disabled submarine boat.

In Figure 1 I have shown, fragmentarily, a submarine boat B having a hull 1, a superstructure 2, and an access hatch trunk 3 extending upwardly through the upper portion of the hull. The upper end of trunk 3 is closed by a suitable cover 4 hinged at 5 and having associated therewith suitable gear 6 for securing the cover tightly closed. A gasket 7 is mounted in the under side of the cover 4 and seats upon the coaming at the upper end of trunk 3 to affect a watertight closure therewith. The cover locking gear in-

cludes a clevis member 8 into which screws the shank of an eye 9, the base of this eye bearing upon the upper face of a manhole cover 10 which normally closes an opening 11 through the main cover 4, this opening constituting a manhole for passage therethrough of the personnel of the disabled boat in the rescue operation. The shank of eye 9 passes through a hub 12 at the center of manhole cover 10, and screws into clevis member 8. In this manner, the locking gear for the main cover 4 is normally secured in position and operates in a known manner to lock this cover closed.

Manhole cover 10 is hinged to main cover 4 at 12^a and is secured in closed position by a hook bolt 13 passing through cover 10 and engaging beneath cover 4. A nut 14 screws upon the upper end of bolt 13 and bears against a collar 15 of an indicating and locking member 16 through the collar 15 of which the bolt 13 slides, the bolt being connected to the collar in a known manner so as to prevent relative turning movement between the bolt and the collar. Normally, nut 14 is turned tight onto the bolt so as to secure the manhole cover 10 in closed position. A gasket 17 is suitably mounted in main cover 4 and coacts with the cover 10 to form a watertight and pressure resistant closure therewith.

A marker buoy 18 is mounted in a buoy compartment or well 19 disposed between superstructure 2 and trunk 3. This buoy may be of any suitable construction and configuration, and is provided with a central sleeve 20. A rod 21 extends through this sleeve and is provided, at its upper end, with an eye 22. A member 23 is suitably secured upon the lower end of rod 21 and is provided, at its lower end, with an element 24 of squared cross section. This element fits snugly into a corresponding socket in upper section 25^a of a release gear housing 25 suitably secured to a reinforcing plate 26 welded or otherwise suitably secured to the inner face of the upper portion of hull 1. This plate and the hull are provided with registering and downwardly tapering openings to accommodate the lower portion of member 23. A shaft 27 is rotatably mounted through

55

60

65

70

75

80

85

90

95

100

lower section 25^b of housing 25, and an operating crank 28 is suitably secured upon the lower end of this shaft. A watertight closure is effected about shaft 27 by means of a stuffing box 29. The shaft 27 is held against end-wise movement by means of a collar 30 secured thereon, this collar fitting into a suitable recess in the housing 25. The upper portion of shaft 27 is threaded and screws into the lower end of element 24. This provides means for releasably securing the buoy 18 in its compartment 19 and for holding it seated upon supporting blocks 31 secured upon the outer face of hull 1. Preferably, a plate 32 is secured to float 18, by suitable brackets 33, this plate serving to cover the upper end of compartment 19 and also forming a continuation of the deck of superstructure 2. As will be noted, the buoy 18 tapers downwardly and the buoy compartment 19 flares upwardly, so that the buoy, when released, can readily pass upwardly out of the compartment.

A cable 34 is coiled within the lower portion of compartment 19, beneath the buoy. One end of the cable is provided with an eye member 35 which is suitably secured, as by means of a shackle 36, to member 23. The other end of the cable is provided with a clevis 37 suitably secured, as by a pin 38, to eye 9. Chamber 19 is provided, in the side thereof adjacent trunk 3, with an offset forming a channel element 39 extending from the top to the bottom of chamber or compartment 19. This channel element accommodates the portion of the cable leading from the coil within compartment 19 and eliminates possibility of fouling of the buoy by the cable, while also preventing possibility of binding of the buoy in its compartment due to contact with the cable. In the event of the boat being disabled and submerged, buoy 18 is released by turning shaft 27 in proper direction to screw this shaft out of element 24 of member 23. This serves also to raise the buoy slightly off of the supporting blocks 31 and, when the buoy is released, it readily rises out of the compartment 19 and floats to the surface, as in Figure 4.

The buoy and the cable provide means for attaching the rescue tank to the cover of the access hatch trunk of the disabled boat. Referring to Figure 2, the rescue tank 40 comprises a central portion 41 and upper and lower heads 42 and 43, respectively, welded or otherwise suitably secured to the central portion. The tank is of circular cross section and is constructed to withstand the high pressures which obtain at great depths. An escape hatch trunk 44 is suitably secured to head 42 and is normally closed by a cover 45 hinged at 46 to the trunk, there being a suitable dog 47 for securing this cover closed.

65 A gasket 48 is suitably mounted in the upper

end of trunk 44 and forms a watertight closure with the cover in a known manner.

A hatch trunk 49 extends through lower head 43 and projects upwardly into tank 40 for a considerable distance. This trunk is 70 provided with an outwardly extending flange 50, spaced a short distance from the lower end of the trunk, and suitably secured, as by riveting, to head 43. A gasket 51 is suitably secured in the lower end of trunk 49 75 and is disposed to seat upon main cover 4 of trunk 3 of the disabled boat. In this connection, it will be noted that the upper face of the outer portion of cover 4, beyond the manhole cover 10, is plane or flat and free 80 from obstructions so that gasket 51 can seat accurately upon cover 4 and, when so seated, will effect a watertight closure therewith, there being sufficient clearance within trunk 49 about the manhole cover 10 to permit of 85 opening and closing thereof.

A cover 52 is provided for closing the upper end of trunk 49, this cover being hinged to the trunk at 53. The cover 52 is normally secured in closed position by swing bolts 90 54, or in any other suitable manner. A gasket 55 is mounted in the underface of cover 52 and seats upon the coaming at the upper end of trunk 49 so as to effect a watertight closure therewith.

A support 56 depends from, and is preferably formed integrally with, cover 52. This support is provided, at its lower end, with an outwardly extending flange 57 to which is bolted, or otherwise suitably secured, a 100 bracket 58. A yoke 59 is rotatably mounted in bracket 58, by means of ball bearings 60 at the upper and the lower ends of the yoke. This yoke carries a guide sheave 61 which receives cable 34, the axis on which the yoke 105 turns being coincident with the center of the portion of the cable which extends downwardly from the sheave.

Trunk 49 is provided, at one side thereof, with an extension 62 which forms, with head 43 and the inner wall of a ballast tank 63 extending about this head, a drum casing. A drum shaft 63^a extends transversely of this casing and is rotatably mounted, at one end, in a bearing sleeve 64 suitably secured to one side wall 62^a of the casing. At its other end, this shaft is rotatably mounted in a combined bearing and stuffing box structure 65 secured to and extending through the other side wall 62^b of the drum casing. This structure 65 provides a watertight closure about the shaft where it extends into the tank from the casing 62. A worm gear 66 is secured upon shaft 63^a and meshes with a worm 67 secured upon the lower end of a shaft 68, the lower portion of which is rotatably mounted in brackets 69 secured to wall 62^b of the drum casing 62. Shaft 68 is rotatably mounted, adjacent its upper end, through a bearing support 70 which is se- 115 120 125 130

cured to one of two brackets 71, these brackets being secured to the surrounding wall of the tank. A beveled gear 72 is secured upon the upper end of shaft 68 and meshes with a beveled gear 73 secured upon a drive shaft 74 rotatably mounted in suitable bearings carried by the brackets 71. The shaft 74 is rotated in a suitable manner, as by means of a handwheel 75 secured upon this shaft. A cable winding drum 76 is keyed upon shaft 63^a for rotation therewith, this drum being rotated in either winding direction or unwinding direction by rotation of handwheel 75 in proper direction. During winding of cable 34 onto and off of the drum, this cable passes over the sheave 61 and through a downwardly flaring guide element 59^a at the lower end of yoke 59. This yoke permits swinging movement of the sheave on a vertical axis to assure proper delivery of the cable to and from the drum.

After the buoy is released, it rises to the surface, as indicated in Figure 4, and serves to mark the position of the disabled submarine boat. In effecting rescue of the personnel of the disabled boat, the tank 40 may either be towed into position or lowered overboard from a rescue boat. The upper end of cable 34 is then detached from the buoy and is suitably secured to one end of a short length of cable, the other end of which is permanently secured to the winding drum, this short length of cable being lead over the sheave 61 and downwardly through the guide member 59^a. The operating crew for the rescue tank then enter the tank through the hatch trunk 44, the cover 45 being opened, after which this cover is secured in closed position. At this time, the ballast tank 63 may be either partly or completely filled with water to decrease the positive buoyancy of the tank 40 to the desired extent. The cable winding drum is then rotated in proper direction to wind cable 34 onto such drum, 45 thus pulling the tank downwardly into such position that the gasket 51 seats upon main cover 4 of hatch trunk 3 of the disabled boat, as in Figures 2 and 6. In Figure 5, the rescue tank is illustrated as approaching the disabled boat, a portion of the cable 34 having been wound onto the drum. Due to the fact that the guide member 59^a is disposed coaxially with trunk 49 of the tank, and eye 9 is disposed centrally of cover 4, gasket 51 55 is guided accurately into position to seat upon cover 4 in concentric relation thereto. After the gasket 51 is seated upon cover 4, the air which is under pressure in the upper portion of trunk 49 is vented into tank 40, 60 by means of a gate valve 77 disposed in a connection 78 to the upper portion of this trunk. This relieves the pressure in the trunk, after which gasket 51 is held firmly pressed upon cover 4, by the pressure of 65 the water exerted upon the upper head 42

and hatch cover 45 of the tank. In this manner, a watertight closure is effected between the lower end of trunk 49 and cover 4 of trunk 3.

After the rescue tank has been properly seated upon cover 4 of the boat hatch trunk, the water in trunk 49 of the tank is blown out of this trunk. For this purpose, I provide suitable means for supplying compressed air to trunk 49 and to ballast tank 63, as well as means for venting the ballast tank and for admitting sea water to trunk 49. I have shown an air flask 79 suitably mounted in tank 40, this flask being connected to an air pipe 80, the lower end of which opens into ballast tank 63 at the top thereof. The upper end of pipe 80 opens through head 42 of tank 40 and may be adapted, in a suitable manner, for connection to an air hose from a suitable source of supply of compressed air, such as a rescue boat. The pipe 80 is controlled by valves 81 and 81^a disposed above and below the connection between this pipe and the flask 79. Valve 81 is normally closed, the pressure of the air from flask 79 being sufficient under most conditions which are liable to be encountered. While I have shown but a single flask 79, any desired number of air flasks may be mounted in the tank 40 and suitably connected in a known manner. The connection between air flask 79 and pipe 80 is controlled by two valves, 82 and 83, between which is connected an air pipe 87 controlled by a valve 86. Valve 86, like valve 81, is normally closed, valves 82 and 83 being also normally closed, valve 81^a being normally open. Air pipe 87 opens at its other end into trunk 49 adjacent the upper end thereof. The lower portion of ballast tank 63 is connected to trunk 49, adjacent the lower end thereof, by a connection 89 which includes two control valves 90 and a sea valve 91, which controls admission of water from the sea. Trunk 49 is provided with a passage 92 formed therein and constituting a continuation of the connection 89.

After the tank 40 has been seated upon cover 4 of the boat hatch trunk, as described, gate valve 77 is opened briefly to vent the air from the trunk, and is then closed. Valves 90 are then opened, valve 91 remaining closed, and valve 86 is opened so as to admit air under pressure to the trunk 49 above the water therein. The water from trunk 49 is blown into the ballast tank 63, the air in this tank above the water therein being vented through a vent pipe 93 controlled by a valve 94. But comparatively low pressure is required for blowing the water out of the trunk 49. After this operation is completed, but a small quantity of water remains in the bottom of the trunk, as illustrated in Figure 7. Cover 52 is then opened, as in Figure 8, and is turned back into such position that

the bracket 58 and associated parts do not obstruct the trunk. Cable 34 is then detached from eye 9 and this eye is screwed out of clevis member 8 permitting the cover locking gear to drop into the boat. Nut 14 of the hook bolt 13 is then loosened and this bolt is turned into position to release the manhole cover 10, which is then swung into open position as in Figure 8. The men from the disabled boat, then pass through the hatch trunk 3, by means of a ladder 95. When this has been accomplished, the clevis member is replaced and the eye bolt is screwed tightly into such member, the lower end of the cable being again secured to the eye bolt, and the manhole cover is then secured in closed position as before. Cover 52 is then secured tightly closed, after which water is admitted from ballast tank 63 to the trunk 49 until the water level in this tank and in the trunk becomes equalized. Valve 90 adjacent the ballast tank is then closed, and the sea valve 91 is opened to admit water from the sea to the trunk so as to equalize the pressures. When admitting water to the trunk 49 from the ballast tank 63, the gate valve 77 is opened so as to vent the trunk, this valve being closed as soon as the water level in the trunk equals the water level in the ballast tank. When the pressures are equalized, the tank tends to rise, due to its positive buoyancy, and the rate at which the tank rises to the surface is controlled by the rate of unwinding of the cable from the drum. If desired, the water remaining in ballast tank 63 can be blown overboard by admitting air to this tank through pipe 80, the sea valve 91 being opened, after which valve 90 adjacent the ballast tank 63 is again closed. When the tank reaches the surface, cover 45 is opened, as in Figure 10, and the men escape from the tank, through trunk 44, by means of a ladder 96. This ladder is connected, at its upper end, and by pin and slot connections 97, to a bracket 98 suitably secured to the head 42 of the tank. When the ladder is in use, its lower end rests upon cover 52, as illustrated. When it is desired to open cover 52, the ladder is raised and is then swung about the connections 97 out of the path of movement of the cover.

Conveniently, the men entering the tank 40 may stand upon the top of ballast tank 63, which provides a suitable platform for this purpose. Obviously, the boat may be provided with as many access hatch trunks and associated marker buoys as may be desirable or necessary, and the rescue tank may make as many trips to and from the boat as may be required for effecting the rescue operation.

Conveniently, the head 42 of the tank is provided with suitably disposed ears 99 for reception of cables 100 for lowering the buoy from a rescue ship and returning it to such ship

What I claim is:

1. In combination, a submarine boat having an access hatch trunk and a main cover therefor, said main cover being provided with a manhole, a cover for the manhole removable exteriorly of the trunk, a buoy exterior of the hull of the boat, means operable from within the hull for releasably securing the buoy to said hull, a cable secured at one end to the manhole cover and having its other end releasably secured to the buoy, a rescue device in the form of a tank provided with a trunk opening through its lower end, the lower end of the tank trunk being adapted to seat upon the upper face of the main cover in spaced relation about the manhole cover, a removable cover for the upper end of the tank trunk, means for venting and flooding the tank trunk, and means operable from within the tank for taking up the cable to draw the tank downwardly into position to seat the lower end of the tank trunk upon the main cover of the boat trunk.

2. In combination, a submarine boat having an access hatch trunk and a main cover therefor, said main cover being provided with a manhole and the upper face of the cover being flat and smooth, a cover for the manhole, means releasable exteriorly of the trunk for securing the manhole cover closed, a buoy, means operable from within the hull of the boat for releasably securing the buoy to said hull, a cable secured at one end to the manhole cover and releasably secured at its other end to the buoy, a rescue device in the form of a tank having a trunk opening through its lower end, a removable cover for the upper end of the tank trunk, means operable from within the tank for taking up and paying out the cable for positioning the lower end of the tank trunk upon the main cover of the boat trunk and for controlling upward movement of the tank away from the boat, and means for flooding and venting the tank trunk.

3. In rescue means of the character described, a tank provided with a trunk opening through its bottom, a removable cover for the upper end of the trunk, a winding drum, and means operable from within the tank for rotating the drum.

4. In rescue means of the character described, a tank, a trunk opening through the bottom of the tank and extending upwardly within the same, a removable cover for the upper end of the trunk, cable guiding means carried by the cover and movable into and out of the trunk in the movement of the cover, a winding drum, and means operable from within the tank for rotating said drum.

5. In rescue means of the character described, a tank, a trunk opening through the bottom of the tank, a removable cover for the upper end of the trunk, cable guiding means carried by the cover and mounted for turning movement on an axis substantially coincident

with the axis of the trunk, said guiding means being movable into and out of the trunk in the movement of the cover, a drum disposed to receive the cable from said guiding means, and means operable from within the tank for rotating the drum.

6. In rescue means of the character described, a tank, a trunk opening through the bottom of the tank and extending upwardly into the same, said trunk being provided with an extension forming with the tank walls a drum casing, a drum rotatably mounted in said casing, means operable from within the tank for rotating said drum, and cable guiding means carried by the cover and movable therewith, said guiding means being moved into and out of the trunk in the closing and opening of the cover.

7. In rescue means of the character described, a tank, a trunk opening through the bottom of the tank, a removable cover for the upper end of the trunk, said trunk extending upwardly within the tank and being provided with an extension forming with the walls of the tank structure a drum casing, a drum rotatably mounted in said casing, means operable from within the tank for rotating the drum, a supporting bracket depending from the cover and movable therewith into and out of the trunk in the closing and opening of said cover, a yoke mounted in the bracket for turning movement on an axis substantially coincident with the axis of the trunk, said yoke being provided at its lower end with a guide member for reception of a cable passing therethrough, and a guide sheave mounted in the yoke and disposed for reception of a cable passing through the guide member and over the sheave to the drum.

8. In combination, a submarine boat having an access hatch structure comprising a trunk extending through the hull and a removable cover therefor, a rescue device in the form of a tank having a hatch trunk opening centrally through its bottom and adapted to seat upon the boat hatch structure to form a water tight closure therewith, cable winding means carried by and operable from within the tank, a cable windable upon said cable winding means for drawing said rescue device downwardly onto the boat hatch structure, cable guiding means for centering the cable relative to the tank trunk, and means for attaching the lower end of the cable to the cover of the boat trunk at the axial center of the latter.

9. In combination, a submarine boat having an access hatch structure comprising a trunk extending through the hull and a removable cover therefor, a rescue device having cable winding means and adapted to seat upon the boat hatch structure to form a water tight closure therewith, and a cable attached to the axial center of said cover and

windable onto said cable winding means for drawing said rescue device downwardly onto said boat hatch structure in centered relation to the boat trunk.

10. In combination, a submarine boat having an access hatch structure comprising a trunk extending through the hull and a removable cover for said trunk, and a cable secured to the axial center of said cover and adapted for attachment to a rescue device for drawing the latter down onto the boat hatch structure in centered relation to said hatch trunk.

11. In combination, a submarine boat having an access hatch structure comprising a trunk extending through the hull and a removable cover therefor, a rescue device having means cooperating with said trunk to form a water tight closure therewith, and means secured to the cover coaxially with said trunk and attached to the rescue device for drawing the latter down onto said hatch structure.

12. In combination, a submarine boat having an access hatch structure comprising a trunk extending through the hull and a main cover therefor provided with a manhole, a cover for said manhole, a rescue device cooperable with said hatch structure to form a water tight closure therewith, and means attached to the manhole cover centrally of the boat trunk and attached to said rescue device for pulling the latter down onto the hatch structure in centered relation thereto.

13. In combination, a submarine boat having an access hatch structure including a trunk extending through the hull and a main cover therefor provided with a manhole, a removable cover for said manhole, a rescue device adapted to seat upon said main cover to form a water tight closure therewith, and means secured to the center of said manhole cover and attachable to said rescue device to pull the latter downwardly onto the main cover and position it substantially concentric with the manhole cover.

14. In combination, a submarine boat, an access hatch trunk extending through the hull, a main cover for said hatch trunk provided with a manhole, a removable cover for said manhole, a rescue device in the form of a tank having a hatch trunk opening centrally through its bottom and adapted to seat upon the main cover to form a water tight closure therewith, cable winding means carried by and operable from within the tank, and a cable secured to said manhole cover substantially centrally thereof and windable onto said cable winding means for drawing the rescue device down onto said main cover, and positioning it thereon about the manhole cover.

15. In combination, a submarine boat having an access hatch structure, closure means for said structure, and a cable secured

to the midpoint of said closure means and adapted for attachment to a rescue device for drawing the latter down into cooperating relation to the hatch structure.

16. In combination, a boat having an access hatch structure, a closure member for said structure, and a cable secured to the midpoint of said member and adapted for attachment to a rescue device for drawing the latter down into operative relation to the hatch structure.

17. In combination, a submarine boat having an access hatch structure comprising a trunk and a main cover therefor provided with a manhole, a cover for the manhole removable exteriorly of the hull, a cable attached at one end to the manhole cover centrally of the trunk, a buoy attachable to the other end of the cable and releasable from within the hull of the boat for carrying said other end of the cable to the surface when the boat is submerged, a rescue device having an entrance member opening through its bottom and adapted to seat upon the hatch structure and form a water tight closure therewith, means for attaching the cable to the rescue device centrally of said entrance member, and cable winding means for drawing the rescue device down onto said hatch structure.

18. In combination, a submarine boat having an access hatch structure comprising a trunk and a cover therefor, a cable attached at one end to the cover centrally thereof, a rescue device having an entrance member opening through its bottom and adapted to seat upon the hatch structure and form a water tight closure therewith, means for attaching the cable to the rescue device centrally of said entrance member, and cable winding means for drawing the rescue device down onto said hatch structure.

In witness whereof, I hereunto subscribe my name this 20th day of August, 1930.

45 HUGO E. GRIESHABER.
